Des. 213,850
Patented Apr. 15, 1969

213,850

HAND DRILL

Melvin H. Boldt, Glenview, Ill., assignor to G. W. Murphy Industries, Inc., Houston, Tex., a corporation of Texas

Filed Apr. 23, 1968, Ser. No. 11,587

Term of patent 14 years

Int. Cl. D8—02

U.S. Cl. D54—14

Fig. 3

Fig. 4

FIGURE 1 is a side elevational view of a hand drill, showing my new design;

FIGURE 2 is a front elevational view of the hand drill illustrated in FIGURE 1;

FIGURE 3 is a top plan view of the hand drill illustrated in FIGURE 1; and

FIGURE 4 is a rear elevational view of the hand drill illustrated in FIGURE 1.

The dominant features of my design reside in the portions shown in full lines.

I claim:

The ornamental design for a hand drill, as shown and described.
